[57] CLAIM

The ornamental design for hand knitter's support stand for yarn packages, substantially as shown and described.

DESCRIPTION

FIG. 1 is a perspective view of the hand knitter's support stand for yarn packages showing my new design; FIG. 2 is a front elevational view thereof on a reduced scale; the broken line showing of the spools of yarn being for illustrative purposes only;

FIG. 3 is a left end elevational view thereof; the end opposite being substantially a mirror image thereof; and FIG. 4 is a top plan view of FIG. 1.

The rear of the hand knitter's support stand for yarn packages is flat and unornamented.
